UNITED STATES PATENT OFFICE.

HENRY AIKEN, OF HOMESTEAD, PENNSYLVANIA.

SHEAR-KNIFE.

SPECIFICATION forming part of Letters Patent No. 402,381, dated April 30, 1889.

Application filed December 11, 1888. Serial No. 293,270. (No model.)

To all whom it may concern:

Be it known that I, HENRY AIKEN, of Homestead, in the county of Allegheny and State of Pennsylvania, have invented a new and useful Improvement in Shear-Knives, of which the following is a full, clear, and exact description, reference being had to the accompanying drawings, forming part of this specification, in which—

10 Figure 1 is a front elevation of my improved shear-knives secured to their holders. Fig. 2 is a side view thereof. Fig. 3 is a face view of the upper knife. Fig. 4 is a side view thereof. Fig. 5 is a face view, and Fig. 6 is a side view, of one of the sections of the lower knife.

Like symbols of reference indicate like parts in each.

I shall first describe the construction of my improved shear-knives, and shall then indicate their advantages and the manner of their use.

In the drawings, Figs. 1, 2, 3, and 4, 2 represents the moving knife of shears for cutting angle-shaped iron, and 3 is the knife-head to which it is secured. The knife is made equilateral, preferably quadrilateral, in outline with rounded corners, and is set vertically in an angular cavity in the face of the knife-head, as shown in Fig. 1, so that two edges 25 and the back of the knife shall be braced and supported by the knife-head and that the outer angle and the adjacent edges of the knife shall be free to act in the operation of shearing. The knife is held to the knife-holder by bolts 4, which pass through registering and symmetrically-placed bolt-holes in the knife and in the knife-holder, as shown in Fig. 2, the bolt-holes in the knife being preferably countersunk on both sides, so that a 30 recess shall be afforded for the head of the bolt, whether one side or the other of the knife is outwardly exposed. (See Figs. 2 and 4.)

The cutting-edge of the bed-knife 6 of the shears is the counterpart in shape of the moving knife, and is set in an angular recess in a knife-holder, 5, which is suitably bolted to the frame of the machine. The knife is made in two parts, *a* and *b*, which are or may be 45 similar in shape, being formed with equal angles at the ends thereof, so that when placed

together, as shown in Fig. 1, the parts shall present a cutting-edge of the desired form, and that when reversed and readjusted, as hereinafter described, they shall present an 55 angular knife of the same shape.

The knives are used in the ordinary manner of shear-knives, the metal being placed on the knife 6 and being sheared off by the descent of the moving knife, though, if desired, 60 the knife 6 may be used as the moving knife and the knife 2 as the stationary knife, or both knives may be movable in shearing the piece.

If the cutting-edges of the knife 2 should 65 become broken or so worn as to be unfit for use without repair or grinding, a new cutting-edge may be presented by removing the bolts 4, turning the knife one-quarter round in the recess of the knife-holder, and the bolts again 70 tightened to hold the knife in place. The knife is thus capable of being turned and of presenting four cutting edges or angles without reversing the faces of the knife in the holder, and four additional cutting-edges may 75 be presented by reversing the faces of the knife and turning the knife one-quarter round from time to time as new cutting-edges may be required, so that the knife possesses eight cutting edges or angles. The lower knife, 6, 80 is constructed to serve a similar purpose, and its parts may be shifted in position four times as the cutting-edge in use becomes worn out, so that all four cutting-edges must be worn before the knives need repair. Thus, when 85 the cutting-edges *a'* *b'*, Fig. 1, become worn out, the sections *a* and *b* may be turned endwise, so as to present fresh cutting-edges *a*² *b*², and when these are worn out the sections 90 may be reversed laterally to present similar cutting-edges *a*³, on the opposite side, as shown in Fig. 6. This reversal is facilitated by the double countersinking of the bolt-holes, as before explained. An additional adjustment of these knife-sections is possible when the cutting-edges at the angle of the knife become 95 more worn than the upper extremities of the sections. In such case the positions of the knife-sections may be exchanged without reversing either of them, so as to bring the upper corners of the sections into the position of the meeting angle, and vice versa. In this

way four additional changes in position are possible.

The advantages of my improvement will be appreciated by those skilled in the art. The length of time during which the knives may be used without repair by simple changes in position is the cause of saving considerable time and labor in the operation of the shears, and prevents the frequent annoyance which is occasioned by the necessity for removing and smithing the knives heretofore in common use.

The nature and scope of my invention is stated in the following claims, each of which states an item of invention unlimited by the elements and limitations contained in the others.

The knife-sections 6 may also be made of different shape from that which I have shown— for example, each may be hexagonal in form.

I claim—

1. An angled shear-knife made in separate interchangeable sections constituting the sides of the angle, substantially as and for the purpose described.

2. An angled shear-knife made in sections which constitute the sides of the angle, each section having its ends formed at equal angles, so that the knife may be shifted to present fresh cutting-edges, substantially as and for the purposes described.

3. An angled shear-knife made in sections which are reversible and which constitute the sides of the angle, each section having its ends formed at equal angles, so that the knife may be shifted to present fresh cutting-edges, substantially as and for the purposes described.

4. An angled shear-knife made in separate interchangeable sections constituting the sides of the angles, and a knife-holder having an angular recess in which the said sections are fitted, substantially as and for the purposes described.

5. A shear-knife holder having an angular recess for reception of the shear-knife, and an equiangular polygonal shear-knife secured therein having shearing-edges which fit against the sides of said recess, in virtue of which any one of its salient angles may be presented in cutting, in combination with a bed-knife having an angular cutting-edge the counterpart of the salient angle of the first-named shear-knife, substantially as and for the purposes described.

In testimony whereof I have hereunto set my hand this 8th day of December, A.D. 1888.

HENRY AIKEN.
